DESIGN FOR A GAME BOARD

Elmer R. Frase, Chicago, Ill.

Application May 31, 1932. Serial No. 43,938

Term of patent 3½ years

To all whom it may concern:

Be it known that I, ELMER R. FRASE, a citizen of the United States, and a resident of the city of Chicago, in the county of Cook and State of Illinois, whose post office address is 4740 North Hamilton Avenue, Chicago, Illinois, have invented a new, original, and ornamental Design for a Game Board, of which the following is a specification, reference being had to the accompanying drawing forming a part thereof.

The figure is a plan view of a game board showing my new design.

The design is of no appreciable thickness.

I claim:

The ornamental design for a game board substantially as shown and described.

ELMER R. FRASE.
